(57) **CLAIM**

The ornamental design for a measuring device for bio-sensor, as shown and described.

DESCRIPTION

FIG. 1 is a front view of a measuring device for bio-sensor of a new design;

FIG. 2 is a back view thereof;

FIG. 3 is a left side view thereof;

FIG. 4 is a right side view thereof;

FIG. 5 is a plan view thereof; and,

FIG. 6 is a bottom plan view thereof.
